LAMP SOCKET ADAPTER

Carl L. Goodlin, Wilkinsburg, and Thomas J. O'Meara, Pittsburgh, Pa., assignors to The Union Switch & Signal Company, Swissvale, Pa., a corporation of Pennsylvania

Original application October 2, 1931, Serial No. 566,572. Divided and this application August 8, 1934, Serial No. 739,000

1 Claim. (Cl. 173—357)

Our invention relates to lamp socket adapters, and particularly to adapters for accurately focusing incandescent lamp filaments in precision devices, such as railway signals, although not limited to this field.

The present application is a division of our co-pending application, Serial No. 566,572, filed on October 2, 1931, for lamp socket adapters.

We will describe one form of adapter embodying our invention, and will then point out the novel features thereof in the claim.

In the accompanying drawing, Fig. 1 is a side view, partially in elevation and partially in section, of an adapter embodying our invention, showing a lamp mounted therein and a support on which the adapter is mounted. Fig. 2 is a top plan view of the adapter shown in Fig. 1.

Similar reference characters refer to similar parts in both views.

Referring first to Fig. 1, the device comprises, in general, a support 2, the adapter 3 of our invention and a lamp 4.

The support 2 comprises an insulating member of inverted substantially cup shape, and a socket member 6 secured thereto as by rivets 7 extending through laterally projecting portions 9 of the socket member 6 and through the insulating member. A terminal screw or binding post 10 is secured to the insulating member and connected to the socket member 6 as by a conducting strap 12 and the rivet 7. A spring connector 14 extends through an aperture 15 in the socket member 2 and is connected to a terminal screw 17. The terminal screws 10 and 17 are provided with heads 19 and nuts 20 at the under and upper sides of the insulating member, respectively. The strap and spring connectors 12 and 14, respectively, may be mounted in grooves in the insulating member as shown.

The socket member 6 is of the bayonet type having an accurately machined cylindrical body portion in which slots 22 of the usual substantially J-shape are disposed at the opposite sides thereof.

Referring now also to Fig. 2, the adapter 3 of our invention comprises a cylindrical base member 24 which is adapted to fit into the socket member 6 with a relatively snug sliding fit, and which is provided adjacent its lower end with diametrically opposite bayonet connector pins 25 for cooperation with the slots 22 in the socket member 6. An inwardly extending flange 26 is formed on the upper end of the base member, and this flange engages, with a certain amount of friction, a lamp socket 27 which extends into the

base member 24. By this means, the remainder of the lamp socket being substantially radially spaced from the base member 24, the lamp socket 27 may be moved along and about the longitudinal axis of the base member 24 and still have sufficient play relative thereto to allow the axes of the lamp socket member 27 and the base member 24 to be tilted angularly about a pivot in the local zone represented by the inwardly extending annular flange 26. For tilting the socket member 27 four screws 28 spaced 90° apart are screwed radially through the side wall of the base member and engage at their inner ends the socket member. The screws 28 are all disposed in the same vertical plane and are longitudinally offset from the flange 26.

In assembling the adapter, assuming there are duplicate supports 2, one in service in a railway signaling device and the other at the place of assembly, the adapter 3 is first placed in the support 2 at the place of assembly. Means including a perforated screw and a telescope, not germane to this invention are then employed to determine the position of the lamp filament relative to the socket member 6. By this means, the exact height, angular position, and position of tilt, if any, of the lamp socket axis relative to the axis of the socket member 6 are determined.

The angular position of the lamp socket 27 relative to the base member 24 is first adjusted by rotating the socket 27 within the flange 26 of the base member to the proper position, after which the height of the lamp socket is adjusted by sliding the lamp socket upwardly or downwardly within the flange 26. The fit between the socket member 27 and the flange 26 of the base member is sufficiently tight so that when the two adjustments just mentioned have been completed, the socket will be temporarily held in its adjusted position by friction. With the height and angular adjustments thus effected, if the filament of the lamp is not at the focal point desired the screws 28 are adjusted until the exact focus is obtained. When the adjustment has been completed, the parts are then fixed in adjusted relation by automatically joining the same as by spot welding or providing bodies 29 and 30 of solder adjacent to the flange 26 and over the outer ends of the screws 28, respectively, the screws preferably being disposed beneath the surface of the member 24 in the manner shown.

As indicated in Fig. 1, when the lamp is placed in the socket 27 it engages a plunger 31 at the lower end of the socket member. The plunger 31, which plunger functions as an electrical con-

necter between the base contact of the lamp 4 and the spring 14 on the support 2, comprises a shank 32 that slidably extends through an insulating plug 33, a lower end head 34 for engagement with the spring 14, an upper end head 35 for engagement with the center contact element of the lamp 4, and a spring 36 for holding the plunger in its upper position until engaged by the lamp. The spring and plunger structure also 10 serves to hold the pins 47 on the lamp 4 more securely in position in the slots 48 of the lamp socket 27.

The form of adapter just described is intended for use with "precision" type lamps, that is, with 15 lamps which have their filaments accurately positioned with respect to the base of the lamp. The adjustments are provided to enable the position of the lamp socket 27 with respect to the base member 24 to be properly located during the process of manufacture without extremely accurate 20 and hence costly machine work, so that when the adapter is placed in the socket member 6 shown in Fig. 1, and a "precision" type lamp is placed in the socket 27, the filament of the lamp will 25 be accurately positioned with respect to the support 2.

Although we have herein shown and described only one form of adapter embodying our invention, it is understood that various changes and modifications may be made therein within the scope of the appended claim without departing from the spirit and scope of our invention. 5

Having thus described our invention, what we claim is:

A lamp socket adapter comprising a cylindrical base member provided at its upper end with an 10 inwardly projecting flange, a lamp socket member extending into said base member and having a relatively tight fit at the flange and clearance 15 below the flange, a plurality of screws screwed through the base member in angular spaced relation a predetermined distance below said flange and cooperating at their inner ends with said socket member to provide tilting adjustment of the socket member relative to the axis of the base member, the members being autogenically joined 20 together in their adjusted positions. 20
